UNITED STATES PATENT OFFICE.

WALTER SCHAFFER, OF BERLIN, GERMANY, ASSIGNOR TO GESELLSCHAFT FÜR DRAHTLOSE TELEGRAPHIE M. B. H. HALLESCHES, OF BERLIN, GERMANY, A CORPORATION OF GERMANY.

ARRANGEMENT FOR AMPLIFYING HIGH-FREQUENCY CURRENTS.

Application filed August 18, 1922. Serial No. 582,609.

To all whom it may concern:

Be it known that I, WALTER SCHAFFER, a citizen of the Republic of Germany and a resident of Berlin, Germany, have invented 5 certain new and useful Improvements in Arrangements for Amplifying High-Frequency Currents, of which the following is a specification, accompanied by drawings.

As is well known, the number of stages 10 through which a high frequency current may be amplified is limited by the fact that, due to internal back coupling, the amplifying arrangement energizes itself. The invention relates to an arrangement which obviates this drawback and makes possible the 15 provision of any desired number of amplifying stages by first amplifying through a suitable number of stages the incoming high frequency, then transforming the frequency 20 of the amplified energy by means of a frequency transformer and further amplifying this alternating frequency through a suitable number of stages. This circuit arrangement may be repeated as often as desired 25 until the desired tone strength is obtained at the end of the amplifying circuit. In accordance with the invention the arrangement is so provided that at each frequency transformation a new amplification 30 is obtained.

In the drawing in which like reference numerals designate like parts in the various views;

Fig. 1 is a diagrammatic representation 35 of an auxiliary circuit arrangement which may be employed for frequency transformation in the practice of the invention;

Fig. 2 is a diagrammatic representation 40 of a modified circuit arrangement adapted for use for the same purpose as the arrangement shown in Fig. 1; and

Fig. 3 is a diagrammatic representation 45 of a circuit arrangement embodying the invention and including the auxiliary circuit arrangements shown in Figs. 1 and 2.

Auxiliary means of widely varying character may be employed for the purpose of frequency transformation. In order, however, to obtain at this frequency transformation also an amplification, it is preferable 50 to use in the high frequency amplification intermediate elements such as the circuit arrangements shown in Figs. 1 and 2 of the drawings. The circuit arrangement shown

in Fig. 1 comprises a direct current source 55 1 for a generator tube 2 which is coupled with the oscillating circuit 3. The oscillating circuit 3 may be tuned to any desired frequency. The cathode side of the current supply circuit of the generator tube 2 60 comprises a three-element tube 4 the grid of which is bridged by a resistance or grid leak 5 for the purpose of the grid discharge. The purpose of the battery 6 is to supply such a negative auxiliary potential to the 65 grid that the generator tube 2 produces oscillations only when the tube 4 is controlled by the energy existing at points 8 and 9. This energy may be obtained from a transformer 7 which constitutes the end of a 70 suitably increased high frequency amplification. The energy is received in the tuned circuit 10 and is rectified by means of any suitable rectifying circuit 11. The direct current potential differences between points 75 8 and 9 are always in proportion with the energy existing in transformer 7. This direct current potential difference controls the cathode tube 2 and thereby also controls the oscillations produced in circuit 3 by 80 said tube. At the same time, due to the generative action of tube 2, these oscillations in circuit 3 have a larger amplitude. By means of a transformer 12 these oscillations are transmitted from oscillating circuit 3 into a further high frequency amplifier set. 85

The circuit arrangement shown in Fig. 2 operates in a manner similar to the arrangement shown in Fig. 1 but differs from the 90 arrangement shown in Fig. 1, in that the control of the oscillations in the circuit 3 is not effected by means of a tube 4 but by directly actuating the grid of the generator tube 2. For this purpose the grid coil 13 95 is inductively connected with the circuit 3 and is connected with the cathode through the condenser 14. The purpose of the auxiliary battery is the same as was the case in Fig. 1; namely, in the absence of oscillations in transformer 7, the battery causes the generator tube 2 not to produce oscillations. As in the arrangement shown in Fig. 1, the resistance 5 serves as a grid leak to prevent the grid potential from becoming 100 excessive.

A complete high frequency circuit arranged in accordance with the present in-

vention is shown in Fig. 3. The receiving antenna 15 is associated with the first high frequency amplifier 17 of a set composed of a suitable number of individual amplifiers, the amplifiers of each set being limited to a number such as will obviate self-energization of the amplifier due to internal back-coupling. It has been found that three amplifiers of the usual construction is as large a number as can be used without injurious back-coupling, and, accordingly, the amplifiers 17 are shown in Fig. 3 of the drawings as three in number. The energy thus amplified is transmitted to a frequency converter 18 such as the one shown in Fig. 1. The energy that is simultaneously transformed and amplified is transmitted through a transformer 7 to a set of amplifiers 19, also of suitable number, and is taken off at 15 7' by a frequency converter 20 such as the one shown in Fig. 2. The amplified and transformed energy is taken off at a converted frequency at 12' and transmitted to an additional amplifier set 21 from which 20 it may again be taken off at 21'. This circuit arrangement may be repeated as often as desired until in the end the total amplification produces the required loudness. Obviously, the above described arrangement 25 may be applied also to low frequency amplification because the frequency converters may without difficulty be operated for low frequency. In view of the fact that in the frequency converter shown in the drawing 30 no back effect can occur between the input and output energy because of the presence of the rectifier, any desired operations may be performed with the frequency converters, e. g. to convert high frequency into another 35 high frequency, or high frequency into a low frequency, low frequency into high frequency or low frequency into another low frequency between the different amplifying stages.

40 45 Having described my invention what I claim is:

1. An arrangement for amplifying alternating currents comprising alternate ampli-

fiers and frequency transformers, each of said transformers comprising a vacuum tube 50 having a grid, a receiving circuit connected to the grid and a rectifier in the receiving circuit connected directly with the grid for causing direct current potential in proportion to the received energy to be impressed 55 on the grid and for preventing any back effect of the transformer on the preceding amplifiers.

2. An arrangement for amplifying alternating currents comprising alternate amplifiers and frequency transformers, each of said transformers having individual amplification and comprising a vacuum tube generator having a grid, a receiving circuit connected to the grid, and rectifiers in the 60 receiving circuit for causing direct current potential in proportion to the received energy to be impressed on the grid and for preventing any back effect of the transformer on the preceding amplifiers. 70

3. An arrangement for amplifying alternating currents comprising a source of energy, means for amplifying the received energy through a suitable number of stages, an oscillation generator, a receiving circuit 75 for controlling the oscillations in the generator, said receiving circuit being arranged to receive the amplified energy from the amplifying means, a rectifier in the receiving circuit for preventing the occurrence of 80 any back effect between the oscillation generator and the amplifying means, and means for further amplifying the energy of the oscillating circuit of the oscillation generator through a suitable number of stages. 85

4. An arrangement for amplifying alternating current, comprising a source of current, a first amplifying means for amplifying said current, a second amplifying means, and a frequency transformer between 90 said first and second means, said frequency transformer having associated therewith a double rectifier arranged so as to prevent back-coupling between said first and second means.

WALTER SCHAFFER.
